RECEPTACLE

Walter Zipper, Vienna, Austria, assignor to
 Evans Case Company, North Attleboro, Mass.,
 a corporation of Massachusetts

Application January 13, 1938, Serial No. 184,882
 In Austria March 10, 1937

11 Claims. (Cl. 206—41)

The invention has to do with a receptacle which is particularly adapted for cigarettes and the like and especially to such a receptacle as may be carried conveniently in a pocket, handbag or the like.

The purpose of the invention is to provide a receptacle in which the contained articles are more or less securely held in position and in which the closed receptacle entirely covers and protects the contents while the open receptacle exposes the contents and may present a portion of each contained article uninclosed and free to be grasped for withdrawal.

In the accompanying drawings Figure 1 is a plan view of the receptacle closed. Fig. 2 is an end elevation of the receptacle open in one position and Fig. 3 is an end elevation of the receptacle open in another position. Fig. 4 is a transverse vertical section on the line 4—4 of Fig. 1. Fig. 5 is a transverse horizontal section on the line 5—5 of Fig. 4. Figs. 6 and 7 are respective views of individual elements of the receptacle. Figs. 8, 9, 10 and 11 are fragmentary sections of portions of the receptacle showing the construction and arrangement of elements in detail.

The receptacle consists of two outer or cover members 20 and 21 which are hinged together on one side at 22. The hinge 22 may preferably be supplied with spring mechanism 23 tending to bias the members 20, 21 to open position. The members 20 and 21 are provided with suitable releasable catches for holding them in closed position. The exact form or shape of the members 20 and 21 is not essential to the present invention. In the drawings the member 20 is illustrated as consisting of a flat rectangular outer plate member from which extend inwardly at the four sides walls 24, 25, 26 and 27. Likewise the cover member 21 is illustrated as consisting of a flat rectangular cover member on which at the four sides are inwardly extending wall members 28, 29, 30 and 31. To hold the cover members 20 and 21 in closed position any suitable catch device may be employed. In the drawings is illustrated a pair of similar catches. One catch is specifically illustrated as consisting of a leaf spring 32 attached at one end 33 to the wall 31 of the cover member 21 and provided with an operating thumb piece 34 which extends through a slot 35 in the wall member 31. At its inner edge adjacent the thumb piece 34 the spring member 32 is provided with a catch 36 which engages an inwardly projecting lip 37 on the wall 27 of the other cover member 20. It will be noted

that the tension of the spring 32 tends to hold the catch 36 in engagement with the lip 37 but pressure on the thumb piece 34 will force the catch 36 inwardly to release the engagement and allow the members 20 and 21 to be forced to open position by the spring 23.

The inner container for the cigarettes or the like consists of two members 38 and 39. These members are identical in construction the member 38 being shown in detail in Fig. 7. Each member 38, 39 consists of a more or less rectangular side member 40 having an end member 41 turned substantially at right angles thereto. There is on the member 40 a bottom member 42 turned substantially at right angles to the member 40 and provided with curled or tubular members at its inner edge alternating with cut-out portions 44. The end member 41 in height is slightly more than the thickness of a cigarette or other article to be held in the receptacle while the wall member 42 is only one half this height. When the two members 38 and 39 are brought together the tubular members 43 of one will fit into the cut-out portions 44 of the other thus producing a more or less continuous channel in which may be placed a pin 45 which may thus form a pintle for the hinge connecting together the two members 38 and 39. At the edge of the member 41 is an inwardly turned lip 46 so arranged that when the members 38 and 39 are fastened together by the pintle 45 the edge of the plate 41 will lie under the inturned member 46 of the other thus forming the members 38 and 39 into a hollow rectangular receptacle.

The members 38 and 39 are preferably made of thin, more or less resilient metal so that they may be slightly deformed from their rectangular form, to cause the edges of the plate 40 to be engaged or disengaged from the holding member 46. Thus the receptacle formed by the members 38 and 39 may be bent to the position indicated in Fig. 3. The plate 40 is cut to form tongues 46 which may be slightly curved or bent inwardly so as to gently, resiliently engage the cigarettes or other articles marked X in Fig. 5 so as to tend to press them against the opposite wall of the receptacle and thus retain them in position. The spring members 46 are alternately and oppositely disposed so that the cigarettes X are held on one side only by a single spring member 46.

The depth of the receptacle formed by the members 38 and 39 may preferably be less than the depth of the receptacle formed by the cover members 20 and 21 and also somewhat less in depth than the cigarettes X or other articles to

be held. Thus the articles **X** may extend beyond the upper edge of the receptacle formed by the members **38** and **39** and so be readily available for grasping to be removed. The springs **46** not merely retain the articles **X** in the receptacle but retain them in position so that the articles do not rely upon each other for being held in the receptacle but each is separately held and when one or more of the articles is removed the rest are not disarranged but each remains substantially in its original orderly place and position.

As illustrated in Fig. 4 the inner receptacle formed by the members **38** and **39** is freely suspended inside the cover members **20** and **21**, the member **38** being suspended from the member **20** and the member **39** being suspended from the member **21**. The specific means illustrated for this suspension consists of a plate **47** suspending the member **38** and a plate **48** suspending the member **39**. These plates are identical and one of them is illustrated in detail in Fig. 6 as consisting of a more or less flat, rectangular member provided at its lower edge with curled or tubular members **49** alternating with cut-out members **50**. The tubular members **49** are held in the cut-out portions **51** between similar curled or tubular members **52** provided at the top edge of the members **38** and **39**. Through the tubular members **49** and **52** extends a pin **53** forming a pintle of a hinge thus formed for joining the members **38** and **39** to the members **47** and **48**.

At their other ends the members **47** and **48** are provided with a tubular hinge member **54** through which pass pins **55** or **56**. The pins **55** and **56** extend beyond the ends of the bearing members **54** and extend into the bearings carried by the members **20** and **21**. These bearings consist of members **57** which may be appropriately fastened by welding or soldering to the inside of the outward corners of the members **20** and **21**. For instance as illustrated in Figs. 10 and 11 the member **57** may be soldered to the walls **24** and **27** of the member **20**. The member **57** is preferably made of malleable metal and in addition to the base portion attached to the members **24** and **27** consists of an extending hook member **58** which lies flat against the wall **27**. The member **58** is in the form and position illustrated in Fig. 10 when first installed. In this position the rod or pin **55** may be inserted against the wall **20** above the hook member **58** and when in this position the member **58** may be turned to the position indicated in Fig. 11 thus enclosing and entrapping the end of the pin **55**. It will be understood that a similar member **57** is similarly provided at the other end of the pin **55** for holding it on the member **20** and members similar to **57** may be provided for holding the opposite ends of the pin **56** in the corresponding corners of the member **21**.

As assembled thus and closed the parts take the position indicated in Fig. 4 when the inner receptacle members **38** and **39** are held in closed position by the catches **46'** and are supported or suspended by the members **47** and **48** it being noted that the hinge **45** is nearly in contact with the hinge **22** but is free and not attached thereto.

When the thumb pieces **34** are pressed to release the catches the members **20** and **21** will be caused to separate by the spring **23**. This movement causes the members **47** and **48** to turn from the vertical position indicated in Fig. 4 to the substantially horizontal position indicated in Fig. 2. This movement causes the inner recep-

tacle **38**, **39** to be lifted so that its bottom is held away from the hinge **22** and the contained articles **X** are lifted and freely exposed for removal. It will be noted in Fig. 4 that the members **47** and **48** form an extension of the members **38** and **39** and enclose and protect the sides of the article **X** when in the position indicated in Fig. 4. In the position indicated in Fig. 2 the members **47** and **48** have lifted the articles **X** which are thus free, open and exposed for removal.

With the device in the position indicated in Fig. 2 the members **38** and **39** may be twisted slightly out of rectangular position and the catches **46'** may thus be released so that the device may come further open and take the position indicated in Fig. 3. In this position the inner receptacle is entirely open and may be readily cleaned and filled with the articles **X** it being understood that the articles **X** may be placed for instance on the member **38** and the member **39** brought over into contact with it and the catches **46'** snapped into place to hold the members **38** and **39** together to form the closed receptacle. Thereafter the members **20** and **21** may be brought together and the entire device held closed by the catches **36**. Articles **X** may be inserted as well as removed while the device is in the condition illustrated in Fig. 2.

The receptacle is illustrated as arranged to receive ten articles **X** and this may be a convenient form to manufacture but the number forms no part of the present invention which may be arranged to receive more or less articles **X**. The members **47** and **48** have been illustrated as flat sheets and such may be convenient and desirable. They form a particularly pleasant appearance, especially when in the position indicated in Fig. 2 in which the members **47** and **48** form a more or less solid background which may be ornamented if desired and from the midst of which project the articles **X**. This construction, however, is not essential as the plates **47** and **48** might be perforated or cut-out, or their entire centers might be removed and the plates consist merely of two end members. It is to be understood that the invention is not limited to any specific embodiment and the particular structure illustrated and described is presented merely for the purpose of clearly illustrating the invention.

The specific devices illustrated in the drawings may be varied in many respects and still form an embodiment of the invention.

I claim as my invention:

1. A receptacle comprising two cover members, a hinge connecting the members to each other at one edge, catches at edges of one member, springs supporting the catches, finger pieces to release the catches, inwardly turned lugs at the edges of the other member releasably engaging the catches to hold the receptacle closed, seats on the members at the edges opposite the hinge, pins carried in the seats, plates on the pins, bearings on the sides of the plates away from the pins, holder members engaging the bearings, a rod holding together the bearings and the holder members, a pintle hinging together the holder members at their edges opposite the plates, releasable means at the sides of the holder members holding them in contact with each other, and resilient members alternately and oppositely disposed in the holder members for engaging articles to be held therein.

2. A receptacle comprising two cover members,

a hinge connecting the members to each other at one edge, releasable means to hold the receptacle closed, seats on the members at the edges opposite the hinge, pins carried in the 5 seats, plates on the pins, bearings on the sides of the plates away from the pins, holder members engaging the bearings, a rod holding together the bearings and the holder members, a pintle hinging together the holder members at 10 their edges opposite the plates, and releasable means at the sides of the holder members holding them in contact with each other, and resilient members alternately and oppositely disposed in the holder members for engaging articles to be held therein.

3. A receptacle comprising two cover members, a hinge connecting the members to each other at one edge, releasable means to hold the receptacle closed, seats on the members at the edges opposite the hinge, pins carried in the seats, plates on 20 the pins, bearings on the sides of the plates away from the pins, holder members engaging the bearings, a rod holding together the bearings and the holder members, a pintle hinging together the holder members at their edges opposite the plates, and releasable means at the sides of the holder members holding them in contact with each other.

4. A receptacle comprising two cover members, a hinge connecting the cover members at one side, 30 two separate members hinged together to form a holder, means connecting the holder to the cover members at the side opposite the hinge and releasable means to keep the holder members together.

35 5. A receptacle comprising two cover members, a hinge connecting the cover members at one side, two separate members hinged together to form a holder, rigid means connecting the holder to the cover members at the side opposite the hinge and 40 releasable means to keep the holder members together.

6. A receptacle comprising two cover members, a hinge connecting the cover members at one side, two separate members hinged together to form 45 a holder, a rigid member hinged to the holder and to the cover members at the side opposite the hinge and releasable means to keep the holder members together.

7. A receptacle comprising two cover members, 50 a hinge connecting the cover members at one

side, a holder comprising two members, a hinge connecting the holder members together at one side and lying near the first mentioned hinge when the receptacle is closed releasable means to keep the holder members together, and means 5 for moving the second mentioned hinge away from the first mentioned hinge as the receptacle opens.

8. A receptacle comprising two cover members, a hinge connecting the cover members at one side, 10 a holder comprising two members, a hinge connecting the holder members together at one side and lying near the first mentioned hinge when the receptacle is closed releasable means to keep the holder member together, and means connect- 15 ing the cover members at the side opposite their hinge to the respective holder members at the side opposite their hinge.

9. A receptacle comprising two cover members, a hinge connecting the cover members at one 20 side, a holder comprising two members releasable means to keep the holder members together, a hinge connecting the holder members together at one side and lying near the first mentioned hinge when the receptacle is closed, means for 25 moving the second mentioned hinge away from the first mentioned hinge as the receptacle opens, and resilient members in the holder members for engaging articles to be held therein.

10. A receptacle comprising two cover members, 30 a hinge connecting the cover members at one side, two separate members hinged together to form a holder lying between the cover members, plates hinged to the outer sides of the cover members and the holder so as to form continuations of the 35 holder when the receptacle is closed and to move the holder outwardly as the receptacle is opened and releasable means to keep the holder members together.

11. A receptacle comprising two cover members, 40 hinged together at one side, two separate members hinged together to form a holder smaller than the cover members and resting adjacent the hinge when the receptacle is closed, and means for moving the holder to substantially the outer 45 edge of the cover members when the receptacle is open and releasable means to keep the holder members together.

WALTER ZIPPER. 50
